MOP CLEANER

James A. Jones, Fayetteville, Ark.

Application January 19, 1938, Serial No. 185,747

5 Claims. (Cl. 15—6)

This invention relates to cleaners for dry mops, brushes and brooms, and particularly to cleaners having a receptacle for the mop, means for loosening dust and dirt from the mop and means for conveying the dust and dirt to a dust receptacle or other place of deposit.

Heretofore, cleaning devices of this character have depended upon suction produced by the ordinary vacuum cleaner fan, and/or upon brushes at the bottom of the receptacle. The bristle brushes usually employed have been found inadequate and ineffective to loosen the dust from the mop and have, moreover, become so filled with dust, lint and dirt as to be wholly or largely ineffective after a short period of use. The location of the brushes at the bottom of the cleaner chamber has also been such as to enable the brushing action to be applied only to a portion of the fringes or fabric of the mop, the attempted agitation of the mop by such an arrangement being found inadequate to loosen and remove the greater part of the dust, lint and dirt from the interior of the mop or even from outer fringes at the sides of the mop.

Another objection to previously-devised mop cleaners of this type has been in the form and configuration of the suction fan, the blades of which, formed with the customary square shoulders, caught and retained any lint or long fiber particles dislodged from the mop and drawn by suction into the fan. The deposit of fibrous matter thus built up soon interfered with the proper action of the cleaner and rendered it incapable of performing its intended function. Attempts to shield the fan by a screen interposed between the mop receptacle and the fan have been unavailing, because the screen almost immediately became so clogged with dirt and fibers from the mop as to terminate the suction action through the cleaner and prevent the passage of air, dust or dirt from the receptacle to the fan and dust outlet.

One of the principal objects of my invention is the provision of a receptacle or chamber into which a mop may be inserted, in association with means for effectively loosening the dust in or on the mop and means for withdrawing the dust and dirt from the receptacle.

A further object is the provision of adequate and thoroughly effective means for brushing and/or beating or jarring the mop to remove or loosen the dust or dirt held thereby.

A further object is the protection or guarding of the mop against excessively severe action of the brushing, beating or shaking elements, with-

out interfering with their proper action or lessening their effectiveness.

A further object is the designing and arrangement of the blades of the suction fan and the other parts of the cleaner to prevent clogging of the apparatus by lodging of dust or dirt in the fan or in the passages connected therewith.

A further object is the provision of a portable, unitary mop cleaner including in compact, convenient and operative relation and arrangement a mop chamber or receptacle, means for effectively agitating the mop, a suction fan, a dust receptacle and an electric motor for operating the fan and mop-agitating means.

These objects are attained by the improvements which constitute my invention and which may be embodied in machines of specifically different construction and arrangement. The preferred form of embodiment is illustrated in the accompanying drawing, wherein,

Figure 1 is an end elevational view of my machine, parts being removed.

Fig. 2 is a central transverse sectional view of the machine shown in Fig. 1.

Fig. 3 is a fragmentary view similar to Fig. 1, 25 from the opposite end of the machine.

Fig. 4 is a side elevational view of the machine,

Fig. 5 is a top plan view of the machine shown in Fig. 1, with the top cover removed,

Fig. 6 is a bottom plan view of the dust bag support shown in Fig. 4,

Fig. 7 is a fragmentary detail view of the suction fan, and

Fig. 8 is an enlarged vertical sectional view of 35 the clutch shown in Fig. 4.

Generally speaking, the machine illustrated comprises a compartment A and space B, the former being preferably provided with a removable top 90 having an opening 90a for introducing a mop into an enclosed mop cleaning chamber or receptacle 4 disposed above a dust hopper 3 communicating through its discharge outlet 42 with a suction fan chamber within a fan casting 2 removably secured to the partition which 45 forms the bottom of compartment A.

Within the mop chamber 4 are arranged a mop guard 12 and a plurality of mop brushes and beaters, the brushes preferably being carried by shafts 5, 6, 7 and 8, and the beaters by shafts 9, 10 and 11, all of the shafts being journaled in suitable bearings in the end walls 40, 41 of the chamber A.

The space B, which may be open, or closed by a removable cover, receives an electric motor 15, 55

- for driving the fan and the mop brushes and beaters. The motor may be supported in any suitable or convenient manner, for example, vertically, by legs or standards 16 fastened to the 5 motor frame and to the base 17 of the machine, which also supports posts 18, preferably of light tubing, upon which the compartment A is mounted. The shaft 19 of motor 15 is preferably extended through an opening in partition 4 and is directly connected to the suction fan 20 within the fan casing 2, preferably by a collar 63 and set screw 64 (Fig. 7). The opposite (lower) end of the vertically arranged motor shaft 19 is set in a suitable bearing and connected by gearing (preferably including suitable reduction gearing, not shown, within gear box 25, miter gears 26, 27, and clutch 28) with a transmission shaft 29, passing through and maintained in vertical and rotatable position by 10 rigid arms 30, 31, secured to one end of the machine (see Fig. 4). At its upper end shaft 29 is connected, by miter gears 32, 33, with brush shaft 7, which is geared to brush shafts 5, 6 and 8 for simultaneous rotation of the shafts 5, 6, 20 7 and 8 through rotation of the gears 35, 36, 37 and 38, fixed to the respective shafts.
- The rotatable shafts 5, 6, 7 and 8 may be either hollow or solid. They carry series of brush fingers or elements, 60, 60a, which may be formed 30 of bristles or other suitable resilient material, but are preferably of resilient rubber, vulcanized directly to the shafts, keyed thereto, or secured in any suitable manner within apertures, sockets or recesses formed in the hollow or solid shafts.
- 35 The fingers are preferably tapered longitudinally to facilitate their passing through the fringes of the mop and allow lint to glide easily off of them under the action of the air current from the fan 20.
- 40 The shafts 9, 10 and 11 have affixed to them series of beater, picker or agitator elements, preferably rigid and slightly curved. These elements may be blades or fingers of sheet steel, wood or hard rubber, set in sockets in the shafts, 45 but are preferably in the form of metal fingers 61 integral with their respective supporting shafts. The beater fingers 61 preferably operate with oscillatory or rocking action imparted to the shafts 9, 10 and 11 by suitable connections 50 (Fig. 3), by means of which the rotation of shaft 5 effects the rocking or oscillatory movement of shafts 9, 10 and 11, through a substantial arc, preferably of 90 degrees.
- The brush shafts 5, 6, 7 and 8 and beater 55 shafts 9, 10 and 11 are mounted lengthwise in the mop chamber and so located therein as to engage and act upon the bottom and sides of the mop or brush inserted within the mop chamber 4 for cleaning.
- 60 To prevent damage to the mop from the brush or beater elements, and especially from the latter, the extent to which the mop may be introduced into chamber 4 is limited or governed by a mop guard 12 extending throughout practically the entire length and width of the chamber. Guard 12 is preferably constructed in the form of an open wire tray, basket or cage comprising a top rectangular frame 83 with depending side and bottom bars preferably formed as 65 integral loops 84. The guard may be held in position within the mop chamber 4 by any suitable means, such as screws 51 inserted through eyes 52 formed in the guard 12 and extending into suitably located screw-threaded apertures or 70 sockets in the end walls 40, 41. When in posi-

tion the guard 12, which receives the mop to be cleaned, is enclosed, on three sides throughout the entire extent of the mop chamber, by the rotating and oscillating fingers described.

The guard 12 and shafts 5, 6, 7, 8, 9, 10 and 11 are so arranged and disposed that the brush fingers 60, 60a, and beater fingers 61 will not come into contact with the guard and the rigid beater fingers will not project so far into the material of the mop or brush as to tear or otherwise damage it. The guard effectively prevents the mop from being drawn between the rotating bottom brush and/or beater shafts or fingers, but permits the brush fingers at the side of the chamber to reach well into the guard and function normally against the material of the mop. The fingers of the bottom brushes act upon the portion of the mop which extends beyond the open bottom of the guard 12, and the fingers of the rock-shafts 9, 10 and 11 pass without interference between the fingers of the brushes carried by the other shafts.

The bottom of chamber 4 is formed by the inwardly sloping walls of hopper 3, which separates the mop chamber from the fan chamber. 25 The central outlet opening 42 of hopper 3 registers with an opening 62 in the top of the fan casing 2.

The fan, rotatably mounted within casing 2, preferably comprises sloping fan blades 65 integral with fan plate 66, and a collar 68 adapted to be secured upon shaft 19 by a set screw 64, the entire fan being of simple, efficient and economical construction, preferably formed of sheet metal and so arranged as to be capable of being uncovered by removal of a single cover (casing 2).

The fan chamber outlet 43 is adapted to be connected with a dust bag 67, preferably at about its middle, as shown; the bag stands in vertical 40 position when inflated and terminates in a collar 68 capable of fitting snugly over a dust receptacle 69, which may be of cardboard or other inexpensive material, to be thrown away when filled.

As a convenient means of removably supporting the receptacle 69 upon the machine, a tapered socket 70 on the bottom of the receptacle is adapted to be slid over and receive a rigid tongue or projection 71 secured to the base 17 50 of the machine.

The entire machine, as illustrated, is preferably supported upon a portable base 17 mounted on rollers 59, and may be enclosed within a cover which may be removable to permit access to the 55 interior for cleaning, lubricating and repairs.

Power for operation of motor 15 may be obtained by the usual extension cord or cable 15a electrically connected with the motor and provided with terminals 15b adapted to be plugged 60 into any ordinary floor or wall socket, and a switch 15c for starting and stopping the motor.

In order to prevent injury to the motor 15 in the event that an excessive load were thrown upon transmission shaft 29 by an obstruction 65 encountered by any of the operating shafts of the machine, I form the transmission shaft in two parts 29, 29a, adapted to be connected by a clutch. The clutch comprises cone clutch members 72, 73, the former being secured to 70 shaft 29 by screw 74 and member 73 being formed with a recess 75 to receive a coil spring 76 detachably secured at one end to the bearing bracket 77 by having its end set into a recess 78 in the bracket, and having its opposite end set into 75

a fiber washer 80, which prevents the spring from turning with the clutch and forms an end thrust bearing for the spring. Clutch member 73 has a key or feather 81 which causes it to rotate with shaft 29a, while permitting a slight axial movement on the shaft when necessary. Whenever an obstruction tends to throw an extra load on shaft 29, the resilient connection afforded by spring 75 permits the upper part 29 of the transmission shaft to stop while the lower part continues to rotate with the motor.

The machine described hereinbefore, although referred to as a mop cleaner, is intended and adapted for cleaning brushes and brooms as well. 15 Preferably the machine is so constructed that when it is ready for use, with its top 90 on, it presents an opening 90a to the mop chamber which is relatively narrow and may be of considerably less width than the width of the machine. 20 By thus concentrating the inward air current upon a small area the suction strength is so increased as to prevent the escape of dust or lint from chamber 4 after the mop is inserted in the opening 90a.

25 In order to operate the cleaner it is only necessary to plug in the extension cord 15a, turn the switch 15c to start the motor 15, and insert the mop or brush into chamber 4 through opening 90a in top 90.

30 When in position the mop or brush to be cleaned rests upon cross bars 84 of guard 12 and is surrounded on three sides by agitating brushes, the upper brushes, on shafts 5, 8, rotating in opposite directions, (clockwise and counter-clockwise, respectively) thus tending to draw the mop into the chamber into a position where it may be effectively acted upon by the fingers 60a of the bottom brushes, each of which rotates in a direction opposite to the rotation of the other bottom brush and the adjacent side brush. 35 For example, the brush fingers 60 of the side brush carried by shaft 5 and the fingers 60a of the bottom brush on shaft 7 rotate clockwise, while the fingers 60a on shaft 6 and fingers 60 on shaft 8 rotate counter-clockwise. By these opposing movements the brushes exert a back and forth movement, resembling a kneading action, upon the mop fabric or fringes, while the rocking of the metal fingers 61 opens up and 40 combs the fringes to loosen the dust and lint, keep such matter agitated and enable it to be removed by the combined effect of the fingers 60, 60a and the suction created by fan blades 65.

Dust and lint removed from the mop in chamber 4 are either drawn directly into the fan chamber through openings 42, 62, or, falling upon hopper 3, slide downwardly to the center and enter the fan chamber through the same openings, whence the extracted matter is blown by 45 the fan through outlet 43 into dust bag 67. Due to the sloping configuration of the fan blades (as shown in Fig. 7), lint, instead of becoming lodged in or on the fan, passes outwardly freely with the air current.

50 When it is desired to empty the dust receptacle 68 or to replace it by a new one, collar 68 is lifted off the receptacle, leaving the receptacle 68 free to be withdrawn from the machine by 55 removing the socket 70 from tongue 71 (see Figs. 4 and 6).

I claim:

1. A cleaner of the character described, comprising a container having a mop chamber adapted to receive a mop or similar article to be cleaned, said chamber having a dust outlet, dust-removing means communicating with said outlet, resilient brushes rotatably mounted in said mop chamber at the bottom and sides thereof, and rigid beaters rockably mounted in said mop chamber between said bottom brushes. 10

2. A cleaner of the character described, comprising a mop chamber, a mop guard supported in said chamber and adapted to receive a mop to be cleaned, and brushes rotatably mounted in said chamber at the bottom and sides thereof, 15 said guard having openings in its sides and bottom adjacent said brushes.

3. A cleaner of the character described, comprising a mop cleaning chamber, dust-removing means communicating with said chamber and 20 having a dust outlet, a mop guard supported in the upper part of said chamber and adapted to receive a mop to be cleaned, brush shafts rotatably mounted in said chamber and extending along the sides of said guard, parallel rotatable brush shafts and rockable beater shafts mounted in the bottom portion of said mop chamber adjacent the bottom of said guard, series of resilient fingers on said brush shafts and series of rigid fingers on said beater shafts, said guard 25 having openings permitting limited access of said fingers to the mop in said guard, and means for operating said dust-removing means and said brush shafts. 30

4. A cleaner of the character described, comprising a mop chamber, a cage constructed of spaced rods forming a mop guard suspended in the top portion of said chamber and adapted to receive a mop or similar article to be cleaned, said guard being spaced from opposite walls of 35 said chamber, resilient brushes rotatably supported in the bottom portion of said chamber below said guard and resilient brushes in the upper part of said chamber adjacent the opposite sides of said guard between the sides of said guard and the walls of said chamber, and means for rotating said brushes. 40

5. A cleaner of the character described, comprising a container, having a mop cleaning chamber therein, the bottom of said chamber having an opening therein, suction means communicating with said opening, an open-top guard cage suspended in the upper part of said mop chamber and spaced from opposite walls thereof, upper brush shafts rotatably supported in the upper portion of said mop chamber along opposite sides of said guard in the spaces between said guard and the adjacent walls of said mop chamber, lower brush shafts rotatably supported in said mop chamber below the bottom of said guard, beater shafts rockably mounted in said mop chamber adjacent said lower brush shafts, series of resilient fingers on said brush shafts, series of rigid fingers on said beater shafts, said guard cage being adapted to receive a mop or 50 similar article to be cleaned and having openings in its bottom and sides permitting access of said fingers to the mop in said guard cage, and means for rotating said brush shafts and oscillating said beater shafts. 55
